Primary Examiner—Carmen H. Vales-Lado
Attorney, Agent, or Firm—Rhodes, Coats & Bennett, L.L.P.[57] **CLAIM**

The ornamental design for a china cabinet, as shown and described.

DESCRIPTION

FIG. 1 is a left front perspective view of a china cabinet showing our new design;

FIG. 2 is a front elevational view thereof; and,

FIG. 3 is a side view, the opposite side being a mirror image of the side shown.

The top, bottom and rear views are not shown and form no part of the claimed design. The dashed lines represent environmental elements only and form no part of the claimed design.
